Mar Firmsan
By his Attorney S. J. Cox

UNITED STATES PATENT OFFICE.

MAX FIRMAN, OF BROOKLYN, NEW YORK.

LIGHTING-FIXTURE.

1,397,274.

Specification of Letters Patent. Patented Nov. 15, 1921.

Application filed September 10, 1920. Serial No. 409,333.

To all whom it may concern:

Be it known that I, MAX FIRMAN, a citizen of the United States, and a resident of the borough of Brooklyn, county of Kings, city 5 and State of New York, have invented certain new and useful Improvements in Lighting-Fixtures, of which the following is a specification.

The improvements relate to lighting fixtures and more particularly to that class of lighting fixtures, in which an incandescent lamp is surrounded by a globe and a reflector is positioned over the globe and lamp for the purpose of effecting what is known as 15 indirect illumination.

The objects of the improvements, among others, are to produce a lighting fixture of the character specified in which the parts are so constructed and arranged that the 20 operations of manufacturing and assembling them are simplified, and a strong, light, and very effective device is produced. They are illustrated in the accompanying drawing, in which the figure represents a vertical medial 25 section of a lighting fixture embodying the improvements, and connected with an incandescent electric lamp and socket.

The globe A consists of four integral parts made of translucent material. They are the 30 swelled or convex portion A' surrounding the lamp terminating in the concave pointed portion A², the contracted and inwardly curved portion A³ and the grooved portion A⁴.

The reflector B comprises a concave body portion B², the beaded edge B', the upwardly extending annular step B³, the inwardly curved portion B⁴, and the collar B⁵, all of these parts being integral and preferably made of metal with a reflective surface.

Secured within the collar B⁵ by a rivet E² is a clamping ring E having eyes E' in its outwardly turned extremities to receive a 45 clamping screw or similar device for connecting the entire fixture with the lamp socket F.

The globe A is secured to the reflector B by means of screws D threaded in openings 50 of the vertical step B³ and engaging the groove A⁴ of the globe A. The lamp C is

preferably of the form shown in the drawing or some similar form, and the source of light is therefore in the lower part of the globe A and below the reflector B.

Several important results are brought about by this construction and arrangement, in addition to the obvious advantages resulting from the integral construction of the globe and reflector parts, and the provisions 55 for assembling and supporting them. The rays of light passing upwardly from the bulb of the lamp C are reflected downwardly first by the concave portion of the globe A³, and second by the part B² of the reflector, as well as by the upper part B⁴ of the reflector. In this manner, and on account of the reflection and re-reflection of the light rays between the translucent globe and the metal reflector, substantially all of 60 the upwardly projected rays, and some of the downwardly projected rays, of light are 65 intercepted and diffused so that a soft highly illuminative light, in which all the rays are utilized, is produced. The globe produces 70 excellent results when made of translucent, but not transparent, material, and in the form illustrated and described. Other material may however be employed, and the form of the globe may be modified to secure 75 different or modified results. The form and material of the reflector may also be varied without departing from the scope of the 80 improvements, but the present form and present polished sheet metal composition of 85 the reflector produce excellent results.

In assembling the fixture it is only necessary to secure the reflector to the lamp socket and then secure the globe within the reflector by placing its upper edges against 90 the cover portion B⁴ and engaging the groove A⁴ with the screws D. This is but the work of a few moments and can be performed by any person of ordinary intelligence.

What I claim is:

In a lighting fixture, the combination of a support, a single-piece reflector having an inner downwardly convex portion, an intermediate annular vertical portion, and an 100 outer downwardly concave portion, a single-piece globe of translucent material having

an annular groove at its top fitting within the vertical portion of the reflector, and an outwardly concave portion opposed to the outer portion of the reflector, supporting means for the globe carried by the vertical portion of the reflector and engaging the groove, and means carried by the inner por-

tion of the reflector for attaching the same to the support.

Witness my hand this 25th day of August, 1920, at the city of New York, in the county and State of New York.

MAX FIRMAN.
